UNITED STATES PATENT OFFICE

96,199

DESIGN FOR A TRAY AND GAME BOARD

George Vincent Post, Chicago, Ill.

Application April 3, 1935, Serial No. 56,195

Term of patent 3½ years

To all whom it may concern:

Be it known that I, George Vincent Post, a citizen of the United States, residing in Chicago, in the county of Cook and State of Illinois, have invented a new, original, and ornamental Design for a Tray and Game Board, of which the following is a specification, reference being had to the accompanying drawing, forming part thereof.

In the drawing:

The figure is a perspective view of a tray and game board, showing my new design.

I claim:

The ornamental design for a tray and game board as shown.

GEORGE VINCENT POST.
